UNITED STATES PATENT OFFICE.

HENRY J. GOSLING, OF PHILADELPHIA, PENNSYLVANIA.

FILE-CUTTING MACHINE.

SPECIFICATION forming part of Letters Patent No. 365,469, dated June 28, 1887.

Application filed March 3, 1887. Serial No. 229,629. (No model.)

To all whom it may concern:

Be it known that I, HENRY J. GOSLING, a citizen of the United States, and a resident of Philadelphia, Pennsylvania, have invented 5 certain new and useful Improvements in File-Cutting Mechanism, of which the following is a full, clear, and exact description, reference being had to the annexed drawings, making part hereof.

10 My invention relates most particularly to mechanism which will operate to graduate the effect of the successive strokes of the chisel in a file-cutting machine as the wider part of the file comes under the chisel. The depth 15 and rapidity of the stroke remain the same for the whole length of the file being cut, but the cuts become gradually farther apart as the wider end of the file approaches the chisel. This desideratum has been accomplished before by other and more complicated and costly 20 mechanism than mine. My object is to produce mechanism which will be simple, strong, and durable, which will yet accomplish the desired result and be easily operated.

25 The mechanism which I combine with a file-cutting machine is of itself old in the arts, and it is to its combination with a file-cutter and its adaptation to the rest of the machine and the purposes of the invention that I limit my 30 claim to novelty.

In cutting files the small end of the file is brought by the carriage first under the operation of the chisel, and at the beginning of the cutting I make the feed or motion of the carriage slow, and by my improvement I gradually increase the rapidity of the feed or the speed of the carriage as the wider or more bulky end of the file approaches the chisel. I thus secure fine or close cutting at the small 35 end and gradually widen the distance between the cuts toward the larger end of the file as the feed is increasing in speed under the regular strokes of the chisel.

My device is automatic in its operation.

40 I combine with the ordinary mechanism of a file-machine a pair of cone-pulleys rigged with an automatic shifter to move the belt, which shifter is operated by the motion of the carriage or file-feeding mechanism; but the 45 nature of my mechanism will fully appear from the following description and claims.

In the drawings, Sheet 1, Figure 1 is a per-

spective view of my machine with my improvement attached. Sheet 2, Fig. 2 is a detached vertical longitudinal sectional view of the same, 55 showing the method of combining my improvement with the machine; Fig. 3, an enlarged side view of the detaching mechanism, showing parts in cross-section; Fig. 4, a detached plan view of the bed, carriage, and operating 60 devices; Fig. 5, an end view of the detaching bar and guide; Fig. 6, an end view of the two cone-pulleys with their belt and shifters.

In my description I will not enter into detail as to the parts of the file-cutting machine, 65 because these parts are fully set forth in United States Letters Patent dated March 19, 1885, numbered 318,104, for file-cutting machine.

A is the base-block upon which the machine is set; B, the frame of the machine, to which 70 the operative parts are attached; C, the vertically-vibrating plunger. The holder C' is set in the lower part of the latter, and carries the chisel.

D is a lift pivoted to the frame at D'; E, a 75 treadle pivoted as shown, and connected with the lift D by rod E'. The office of the lift is to raise the plunger, so as to elevate the chisel and release the finished file.

F is a screw-threaded revolving bar, which 80 engages in a half-worm in the lower face of block F'. This block F' is attached to the carriage G, which bears the file being cut.

G' is a catch upon the side of the carriage, which engages in a notch, G'', in the lower 85 edge of the traveling latch H.

H' is a slotted guide-plate to direct the movement of latch H, and is provided with an inner shoulder, I, upon which latter the adjustable cam-piece I' runs, and by which the 90 cam-piece is thrown up to raise the latch and release it from the catch G'.

I'' I' are slots provided with set-screws to adjust the cam-piece backward and forward on the latch, so that the latter may be thrown up 95 at various points in the traverse of the carriage G. The latch H is pivoted at its rear end to the block J, which travels to and fro in the guide-bar J'. This guide-bar J' is bolted to the rear side of frame B. (See Fig. 3.) 100

J'' is a friction-roller set on the rear end of bar J'.

K K' are two cone-pulleys, their ends being set in opposite directions. Pulley K is

mounted upon shaft K'', driven from a main driving-shaft, and pulley K' is mounted upon a short shaft, L. A short traveling belt, M, from pulley K drives pulley K'.

5 L' is a beveled cog-wheel engaging with cog-wheel L'' upon the end of screw-threaded rod F.

Mounted upon the block J is a short standard, N, and the block J and this standard carry two belt-shifters, N' N'.

O is a cord, chain, or band sustaining a weight, O'. This cord passes over roller J'' and is attached to block J.

15 The raising of the plunger C raises an inner cam within the frame away from the vibrating actuating mechanism and throws the plunger temporarily out of service. This mechanism is, however, fully described in my previous patent above referred to.

20 When it is desired to cut a file by my improved device, the carriage G is pushed back and the block J will be drawn back by the weight O' until the belt M is near the smaller extremity of pulley K and near the larger end 25 of pulley K'. The catch G' will also be engaged in notch G'' of latch H. The carriage as it moves forward will draw latch H with it, and consequently block J, thus slowly shifting the belt toward the larger part of pulley K 30 and the smaller part of pulley K'. This will gradually increase the speed of the latter, and consequently that of shaft L, rod F, and the motion of the carriage G. The latch H will thus be drawn through guide-plate H' until 35 the cam-piece I' runs up on shoulder I and raises the latch out of engagement with the catch G'. The cam-piece is so adjusted that this action will occur at the period when the

file has just finished its traverse under the chisel. The weight O' then draws the block J 40 and its connections back and returns the belt M to its original position. Carriage G is then pushed back for a repetition of the operation.

If desired, the weight and cord may be dispensed with and the belt-shifting mechanism 45 may be connected with the rear of carriage G, whereby when the carriage is pushed back by the operator the belt M will be returned to the original position above referred to, and be again shifted by the forward movement of the carriage.

What I claim as new is—

1. In a file-cutting machine, the combination of two cone-pulleys, K K', belt-shifter N', and shaft L, geared to the carriage-driving mechanism, said belt-shifting mechanism being connected with and actuated by the carriage, whereby the speed of the latter is varied as it progresses in its traverse, substantially as described. 60

2. In a file-cutting mechanism, the combination of two cone-pulleys, K K', belt-shifter N', shaft L, geared to the carriage-driving mechanism, said belt-shifting mechanism being connected with latch H, the latter engaging with carriage G, and being provided with cam I', adapted to be raised by shoulder I to disengage latch H from the carriage, and weight and cord O' O, to draw the belt-shifter back when latch H is disengaged from the carriage, substantially as described. 70

HENRY J. GOSLING.
